BY
Richard J. Cook
ATTORNEY

UNITED STATES PATENT OFFICE.

DONALD MCGREGOR, OF TACOMA, WASHINGTON.

STEAM AND AIR HEATER.

Application filed June 16, 1923. Serial No. 645,764.

To all whom it may concern:

Be it known that I, DONALD MCGREGOR, a citizen of the United States, and a resident of Tacoma, Pierce County, Washington, have invented certain new and useful Improvements in Steam and Air Heaters, of which the following is a specification.

This invention relates to improvements in heaters and more particularly to steam and air heaters of that character adapted for heating purposes. It is the principal object of the invention to provide a combination steam and hot air heating plant of economical and durable construction which can be quickly heated to produce steam or hot water for heating or other purposes, and which also provides for the heating of air which may be conducted through pipes in the usual manner to the different rooms of a building for heating or for other uses.

Other objects of the invention reside in the various details of construction and combination of parts embodied by the invention.

In accomplishing these and other objects I have provided the improved details of construction, the preferred forms of which are illustrated in the accompanying drawings, wherein—

Figure 1 is a transverse sectional view of a boiler constructed in accordance with the present invention, showing its steam pipe connection with a radiator and a hot air pipe connection with a floor register.

Figure 2 is a side view of the boiler with parts broken away for better illustration.

Referring more in detail to the drawings—

1 designates a horizontal boiler beneath which is formed a fire box 3, all of which is supported by a rectangular channel beam frame 4 which serves as a supporting base and also as the ash receiver. The fire box is equipped at the front with a door 5 and the base portion with a door 6. Toward the front portion of the fire box are located the usual grate bars 7 and back of these is a transverse bridge wall 8 which extends to about one-half the height of the fire box. The fire box is shorter in length than the boiler and at its rearward end opens into a combustion chamber 10 that extends upwardly well within the outlines of the boiler portion so that the front wall 11 of this chamber about the fire box serves as a flue sheet, as is best illustrated in Figure 1. The

boiler is of cylindrical form and its side walls are formed from a single piece of sheet metal that is rolled at its central portion into cylindrical form with opposite end portions bent outwardly and downwardly to form the outer opposite side walls that inclose the fire box. An arched crown sheet 12 forms the interior walls of the fire box and this is spaced from the outer side walls 13 and connects at its rearward end of the front wall 11 of the combustion chamber.

The construction provides a water arch 14 at opposite sides and across the top of the fire box throughout its length that connects with the boiler through a narrow passage 15 that extends the length of the fire box. A plate 16 forms the rear end wall of the boiler and this is spaced slightly from the rear wall 17 of the combustion chamber providing a narrow wall leg 18 which opens at its upper end into the boiler. Spaced from the front end of the boiler is a flue sheet 20 forming a smoke chamber 21 and at the rear end of the boiler is a smoke box 22 having an opening 23 for connection with a stack. Extending between the front wall 11 of the combustion chamber and the flue sheet 20 are tubes 24 and above these extending between the smoke chamber 21 and box 22 are tubes 26. This construction provides for passage of smoke and heated air from the combustion upwardly and forwardly through the lower set of tubes and then rearwardly through the upper set 90 thereby giving a maximum travel for efficiency.

To insure rigidity and durability of construction and to provide for a passage of air from one side of the boiler to the other, I have tied the opposite walls together by means of a plurality of tubes 31 that are extended through the passage 15 that connects the water arch with the boiler. A water inlet connection 38 connected with the water arch 14 at one side of the fire box and an outlet pipe 39 leads from the upper central portion of the boiler. The pipe 39 may be connected with radiators in the usual manner as is illustrated in Figure 1 by means of a pipe 40 that leads to the radiator 41 and in this way the boiler will serve the steam heating purpose. The particular cylindrical shape of the boiler and upper portion of the fire box provides large intermediate air pockets 35 at opposite sides and I have extended cover plates 36 over these pockets

which are closed at their forward ends by the plate forming the front wall of the fire box and at their rearward ends are closed by the front wall of the combustion chamber.

5 To adapt the device also for heating by air I provide an air inlet opening or pipe 43 leading through a wall 36 into the lower portion of a pocket 35 at one side of the furnace and have provided an outlet pipe 44 leading 10 upwardly from the other air pocket at the opposite side of the furnace. This construction provides that air may be intaken through pipe 43 heated within the first air pocket 35 passed through tubes 31 into the other air 15 pocket where it is heated to greater extent and delivered into the pipe 44.

Having thus described my invention, what I claim as new therein and desire to secure by Letters-Patent, is:

20 1. In a heater of the character described, a water arch forming the side and top walls for a fire box, a cylindrical boiler superimposed longitudinally upon and having water circulating connection with the water arch and with air pockets along opposite sides thereof, and a plurality of air passages connecting the pockets, housing plates secured to the boiler and arch to inclose said pockets, a cold air inlet into one of said pockets and an outlet pipe from the other.

25 2. A heater of the character described, comprising a fire box, a water arch overly-

ing the fire box, a boiler superimposed above the said water arch and communicating with the latter through a narrow, longitudinally 35 extending passage along the base of the boiler; said boiler and arch forming air pockets along opposite sides thereof, housing members secured to the boiler and arch to inclose said pockets, a plurality of air tubes connecting the pockets through the boiler and arch connecting passage, a cold air inlet into one of said pockets and an air outlet pipe leading from the other.

3. In a heater of the character described, 45 a water arch, a steam boiler supported longitudinally on said water arch having its side walls formed from a continuous piece of sheet metal shaped to form the boiler and the outer opposite side walls of the water 50 arch and to provide a narrow longitudinally extending communicating passage between the arch and boiler and providing air pockets at opposite sides between the arch and boiler, a plurality of air tubes connecting the 55 said pockets through the communicating passage between the arch and boiler, housing members inclosing the pockets, a cold air inlet into one of said pockets and an outlet pipe leading from the other pocket.

Signed at Portland, Multnomah County, Oregon, this first day of June 1923.

DONALD McGREGOR.
